US00D755208S

(12) **United States Design Patent**
Jang et al.

(10) **Patent No.:** **US D755,208 S**
(b4) **Date of Patent:** ** **May 3, 2016**

(54) **DISPLAY SCREEN OR PORTION THEREOF
WITH GRAPHICAL USER INTERFACE**

(71) Applicant: **Samsung Electronics Co., Ltd.,**
Suwon-si (KR)

(72) Inventors: **Chul-Ho Jang**, Seoul (KR); **In-Young Choi**, Seoul (KR)

(73) Assignee: **SAMSUNG ELECTRONICS CO., LTD.**, Suwon-Si (KR)

(**) Term: **14 Years**

(21) Appl. No.: **29/509,071**

(22) Filed: **Nov. 13, 2014**

(30) **Foreign Application Priority Data**

Sep. 2, 2014 (KR) 30-2014-0042925

(51) **LOC (10) Cl.** **14-04**

(52) **U.S. Cl.**

USPC **D14/485**

(58) **Field of Classification Search**

USPC D14/485-495; D10/122, 123, 124, 125, D10/126, 128, 6, 1; 700/16

(57) **CLAIM**

The ornamental design for a display screen or portion thereof with graphical user interface, as shown and described.

DESCRIPTION

The FIGURE is a front view of a display screen or portion thereof with graphical user interface showing my new design. The broken lines around the FIGURE show a display screen or portion thereof and form no part of the claimed design. The broken lines within the FIGURE show portions of the graphical user interface that form no part of the claimed design.

1 Claim, 1 Drawing Sheet
